UNITED STATES PATENT OFFICE.

PARLEE H. RUSSELL, OF VAN BUREN, OHIO.

VEHICLE-JACK.

1,223,618.

Specification of Letters Patent.

Patented Apr. 24, 1917.

Application filed April 21, 1915. Serial No. 22,904.

To all whom it may concern:

Be it known that I, PARLEE H. RUSSELL, a citizen of the United States, residing at Van Buren, in the county of Hancock and State 5 of Ohio, have invented certain new and useful Improvements in Vehicle-Jacks, of which the following is a specification.

This invention relates generally to means for lifting the front or rear portion of vehicle bottoms off the ground, as they are moved into operative connection therewith, and is more especially intended to be used as an automobile jack in which the several parts are coöperatively so arranged that the 15 momentum of the auto as it engages the jack carriage causes the said device to engage and retain the axle and adjacent body structure in an elevated position, to relieve the tires from strain and to provide for readily and 20 conveniently repairing and replacing tires or making other desired repairs.

The principal object of my invention is to provide a device of this character which consists of but a few simple and durable parts 25 that are designed to coöperate in an efficient manner with view of positively and effectually supporting the jack carriage mechanism.

Another object is to provide an improved 30 track means to be used in conjunction with the jack carriage in order to compensate for the movement of the latter during the stopping of the auto and to obviate the necessity of employing means for abruptly stopping 35 the machine at a desired point such as would obviously derogate from the efficiency and utility of the device.

Other servient objects will become apparent during the continuance of the following 40 specification.

The above and other objects which will become apparent are accomplished by such means as are shown in their preferred form in the accompanying drawings, described in 45 the following specification and more specifically pointed out in the appended claims.

In the accompanying drawings wherein 50 is shown the preferred form of my invention, like characters designate like parts throughout the several views, and in which;

Figure 1 is a side elevation of my invention showing parts thereof broken away.

Fig. 2 is a front elevation.

Fig. 3 is a detail view.

55 Fig. 4 is a sectional view taken on line 4—4 of Fig. 3.

Fig. 5 is a perspective view of one of the axle engaging blocks.

In reducing my invention to practice, longitudinal supporting members 10 and 11 are 60 first arranged on the ground or floor as the case may be, and secured in spaced relation by any desirable means. The members 10 and 11 may be constructed of any desirable material yet in view of the fact that the conditions will necessarily vary in concurrence with the adoption of my invention, I do not 65 limit myself to any specific material.

Channel irons 12 and 13 are arranged on the respective supporting members 10 and 11 in order to form suitable track structures for guiding the jack carriage and the mechanism carried thereby during the jacking operation. Transverse brace rods 14 span the members 10 and 11 and have their respective 75 extremities rigidly secured to the lifting blocks 15 and 16 as shown at 17 and 18 respectively. The rod 14 is also secured to the supporting members 10 and 11 as at 19 and 20 in order to reinforce the latter and obviate the danger of spreading during the 80 operation of the device.

The front and rear edges of the lifting blocks 15 and 16 are cut slanting as at 21 and 22 in order to facilitate the operation of the 85 machine thereon, so that the adjacent body structure of the latter will be lifted at a desirable angle, sufficient to cause the engagement of the adjacent axle with the respective axle engaging blocks, presently 90 described.

In constructing the jack carriage and different component parts, complementary chair members are employed which consist of spaced apart side portions 23 and 24 having 95 a suitable stirrup 25 formed therein as clearly shown in Fig. 3 from which project upstanding ears 26. The side portions and the stirrup formed therein are preferably constructed of a single section of material, in 100 order to decrease the cost of manufacture and at the same time provide a more durable device.

Axle members 27 and 28 are journaled through the respective side portions 23 and 105 24 adjacent the ends thereof as shown in Fig. 1 in order to revolvably support suitable supporting wheels 29 and 30, the latter being designed to operate in the channel irons 12 and 13 in order to guide the jack carriage during the jacking operation. With 110 view of spacing the supporting wheels from

the inner faces of the side members 23 and 24, bearings 31 are arranged on the axles 27 and 28.

In order to connect the respective chair members, a transverse block or body 32 is employed which is seated in the opposite stirrups 25 as shown, the upstanding extensions 26 carrying suitable means 33 for securing the same in a rigid position, and thus eliminating spreading or otherwise lateral displacement of the chair members. Means may also be employed for connecting the body 32 and the respective side portions of the stirrups 25 as indicated by the numeral 15 34 in Fig. 1, however, it is to be understood that this form of fastening means is merely shown for sake of illustration and that other forms may be substituted in place thereof if it is so desired.

20 Spaced apart axle engaging blocks 35 are arranged on the body 32, which carry depending portions 36 that are secured to the adjacent portion of the body 32 by such means as shown at 37, the entire block forming a substantially inverted L-shaped structure. A series of openings 37' are arranged in proximity to the axle engaging blocks whereby the latter may be easily and quickly moved to various adjusted positions. With 25 view of limiting the movement of the axle on the respective blocks 35, upstanding plates 38 are secured to the front face of the body 32, and have connection with the fastening means 37 as shown in Fig. 1. However, other fastening means 39 are employed which have connection with the plates 38 and the respective block members 35 in order to efficiently support the same 30 in a rigid position.

40 The material used in the construction of the blocks 35 and the respective plates 38, may be varied in accordance with the existing conditions, and it is to be understood that I am not limited to any specific form.

45 In the operation of my invention, the respective jack carriage is moved into the position shown in Fig. 1 adjacent the forward extremities of the adjacent irons 12 and 13 respectively. If the front portion of the 50 machine or vehicle is to be lifted for purpose of repair or otherwise, the said machine or vehicle is operated so that the front wheels will engage the front inclined faces 21 of the lifting blocks 15 and 16. During 55 the travel of the front wheels of the vehicle or machine on these inclined faces, the adjacent body structure will be lifted at an angle, so that the front axle portion will engage the upper face of the axle engaging

60 blocks 35, the forward movement of the axle on the blocks being limited through the medium of the plates 38. The vehicle is then brought to a stop, which in usual instances requires a distance of from 2 to 3 feet, during 65 which operation the jack carriage will

travel on the respective track means. After the jacking carriage is moved out of proximity to the lifting blocks it will be understood that the front wheels of the machine or vehicle will be in an elevated position 70 thus facilitating repair or the change of the tires as pointed out hereinbefore.

In reducing my invention to practice I find that the form referred to herein as the most practical and preferred embodiment is 75 the most efficient, yet realizing that certain conditions will necessarily vary in concurrence with the adoption of my invention, I desire to emphasize the fact that various minor changes in details of construction and proportion of parts may be resorted to when required without sacrificing any of the advantages of my invention as defined in the appended claims.

Having thus fully described my invention, what I claim as new and desire to secure by Letters Patent is:

1. In a device of the character described, a track structure, guide means, lifting blocks arranged in proximity to said guide means, a jack carriage movably mounted on said guide means, said carriage including complementary chair structures, and means connecting said chair structures, substantially as described.

2. In a device of the character described, a track structure, guide means, lifting blocks arranged in proximity to said guide means, a jack carriage movable on said guide means, said carriage including complementary chair structures, a stirrup formed in each of said chair structures, a body structure seated in said stirrups for connecting said chair structures, and axle engaging blocks carried by said body structure, substantially as described.

3. In a device of the character described, the combination with track structure, guide means, and lifting blocks arranged in proximity thereto, of a jack carriage including chair structures, supporting wheels carried by each of said chair structures and engaging said guide means, means connecting said chair structures, axle engaging members carried by said means and detachable plates carried by said means and said axle engaging members, substantially as described.

4. In a device of the character described, the combination with a track structure, guide means, and lifting blocks arranged in proximity thereto, of a jack carriage including spaced chair structures arranged to extend longitudinally with respect to said track structure, stirrups formed intermediate the ends of said chair structures, a block seated in said stirrups connecting said chair structures, supporting wheels carried by said chair structures and operable on said track structure, spaced axle supporting

blocks arranged on said connecting block, and detachable plates fixed to said connecting block and the said supporting block to limit movement of an axle on said supporting blocks, as and for the purpose specified.

5. In a device of the character described, the combination with a track structure, and lifting blocks arranged in proximity thereto, of a jack carriage including spaced chair structures arranged longitudinally with respect to said track structure, oppositely projecting bearings on said chair structures, supporting wheels connected with said bearings to operate on said track structure, 15 stirrups formed intermediate the ends of said chair structures, a block seated in said stirrups to connect said chair structures, said block projecting above said chair struc-

tures, L-shaped axle supporting blocks detachably affixed to said connecting blocks, 20 one portion of said supporting blocks overlying the upper edge of said connecting blocks and the other portion thereof engaging with one longitudinal face thereof, and detachable plates affixed to said connecting 25 blocks and said supporting blocks to project above the latter and limit movement of the axle on said supporting blocks, as and for the purpose specified.

In testimony whereof I affix my signature 30 in presence of two witnesses.

PARLEE H. RUSSELL.
